UNITED STATES PATENT OFFICE.

JOSEPH CALVIN WEBB, OF TWIN FALLS, IDAHO.

ENVELOP-CLOSURE.

1,110,019.

Specification of Letters Patent. Patented Sept. 8, 1914.

Application filed Aug. 21, 1913. Serial No. 785,978.

To all whom it may concern:

Be it known that I, JOSEPH CALVIN WEBB, a citizen of the United States, residing at Twin Falls, in the county of Twin Falls 5 and State of Idaho, have invented a new and useful Envelop-Closure, of which the following is a specification.

The present invention appertains generally to envelopes and other containers, and 10 relates more particularly to a novel and improved closure therefor.

It is the object of the present invention to provide novel means for sealing an envelop or other container, without the assistance of 15 glue, paste, or other adhesive, and whereby the envelop or container may not be opened without detection.

It is also the object of the present invention to provide a simple and inexpensive 20 closure, which will not encumber the envelop or container, and which will permit the container to be readily sealed or closed, in a positive, reliable and efficient manner.

As a more specific object, the present invention aims to provide an envelop or other 25 container embodying a closure flap adapted to be tucked through a slot, a pocket being provided to receive that portion of the closure flap tucked through the slot, and the 30 pocket and closure flap having a unique interengaging means for locking the closure flap against withdrawal.

With the foregoing general objects outlined, and with other objects in view, which 35 will be apparent as the nature of the invention is better understood, the present invention resides in the combination and arrangement of parts and in the details of construction hereinafter described and 40 claimed, it being understood that changes in the precise embodiment of the invention herein disclosed, can be made within the scope of what is claimed, without departing from the spirit of the invention.

45 The invention has been illustrated in its preferred embodiments in the accompanying drawing, wherein:—

Figure 1 is a perspective view of an envelop embodying the improved closure, the 50 closure flap being illustrated as starting to enter the slot. Fig. 2 is a fragmental perspective view of the back of the envelop, the pocket being unfolded, to illustrate the formation thereof. Fig. 3 is a fragmental plan 55 view of the envelop in sealed condition, the front or face of the envelop being removed,

and the closure flap being illustrated in dotted lines. Figs. 4 and 5 are enlarged sectional views, taken on the lines 4-4 and 5-5 of Fig. 3. Fig. 6 is a view similar to 60 Fig. 3, illustrating a variation or modification.

Referring specifically to the drawing, the envelop illustrated therein, embodies the front or facing 1, and the back 2, the same 65 being united in any convenient manner, and being provided with a mouth at one end, although it is to be understood that the present invention may be incorporated in various styles or sizes of envelopes, as well as 70 paper boxes or receptacles, which are constructed of paper or other flexible stock. The envelop illustrated is therefore to be taken as typical only, or as illustrating an arbitrary or conventional container.

In carrying out the present invention, the 75 end of the front or facing 1 is provided with a closure flap 3 adapted to swing over the mouth of the envelop, as usual. This closure flap 3 is provided with a tapered tongue 4, 80 the free end of which is provided with a longitudinal slit or cut 5 defining a pair of yielding tabs or leaves 6, which are provided with oppositely or laterally projecting hooks or catches 7 at the side edges of the tongue. 85

The end of the back 2, illustrated in Figs. 2 to 5 inclusive, is provided with an in-turned flap 8 complementing the closure flap 3, and is further provided with a transverse slot 9 adjoining and parallel with the 90 mouth of the envelop. The flap 8 is provided with a tapered extension 10, the side edges of which are provided with the lips or tabs 11. The lips or tabs 11 are folded or bent back upon the extension 10, and the 95 flap 8 is folded upon the inner side or face of the back 2, the lips 11 being glued or adhesively secured to the inner side of the back 2, whereby the extension 10 defines a tapered pocket 12, having its ends open. 100 The slot 9 forms a mouth for the pocket 12, it being noted that the basal portion of the extension 10 is folded over the slot 9, in order that when the tongue of the closure flap is inserted or tucked through the slot 9, the same will be directed into the 105 pocket 12.

The taper of the tongue 4 and extension 10 is practically the same, and the tongue and extension are also preferably of the same 110 width, in order that the tongue may fit snugly within the pocket.

In practice, after the envelop or container is filled, the free end of the tongue 4, or the tabs 6, are inserted through the slot 9, and the tongue is then forced home through the 5 internal pocket 12, the tongue being of such a length, that its free end or hooks 7, will pass completely through the pocket. Thus, as the hooks 7 pass through the inner or smaller end of the pocket, they will be 10 forced together, the tabs 6 being adapted to yield when slid along the edges of the pocket, and when the hoops 7 are forced through the inner or smaller end of the pocket, they will expand and lock over the 15 inner end of the pocket, as illustrated in Fig. 3. This will result in the closure flap being locked in position, in order that the envelop may not be opened without detection. In this condition, the envelop may be 20 mailed or transported without the liability of the envelop being opened by malicious or unauthorized persons, without so mutilating or tearing the envelop, as can be readily detected. Attention is directed to the fact that 25 the catches or hooks 7, for the tabs 6 carrying the catches, are yieldable toward each other in the plane of the tongue, in order that when the tongue is inserted into the pocket, the edges of the pocket converging 30 toward the inner end thereof, will cause the catches or hooks to be pressed together, whereby the catches or hooks will snap over the inner end of the pocket when the tongue is forced home.

35 The present closure may be employed for various purposes, as above intimated, and in some instances, it may be desirable to construct the closure flap of several plies or thicknesses in order to render the same sufficiently stiff, as to resist tearing, in the attempt to extract or withdraw the tongue of 40 the closure flap from the pocket. It will be evident that the present closure device permits the envelop or container to be sealed 45 without the employment of the usual glued or gummed closure flap. The present closure flap may also be more quickly attached to the back of the envelop, than where it is necessary to lick or moisten the 50 closure flap of the prevailing type.

In the variation illustrated in Fig. 6, the envelop is the same as the one above described, with the exception of the pocket. The pocket 12' in this variation is 55 constructed of a separate blank of paper or

other material, the blank embodying a tapered or trapezoidal body 10' having the lips or tabs 11' at its side edges. The lips 11' are bent back and secured to the back 2 of the envelop, whereby the pocket 12' is associated with the slot 9, similar to the pocket 12 above described. The operation of the modification is the same as the operation of the preferred form described hereinbefore, and need not be reiterated.

Having thus described the invention, what is claimed as new is:—

1. A container having a closure flap and an internal pocket carried by one side, the closure flap having a tapered tongue, the 70 free end of the tongue having a longitudinal slit forming tabs yieldable in the plane of the tongue, the tabs having laterally projecting hooks, the pocket having its inner end open and having its edges converging 75 toward the inner end, to press the tabs together when the tongue is inserted, whereby the hooks will snap over the inner end of the pocket when the tongue is forced home.

2. A container having a closure flap provided with a tongue, and an internal pocket embodying a member having side lips, the lips being bent back and secured to one wall of the container, the tongue being insertible through the pocket, and the tongue having 85 catches to slide along the edges of the pocket and to snap over the inner end thereof.

3. An envelop having a slot in one side adjoining the mouth, the other side having a 90 closure flap provided with a tongue insertible through the slot, the first mentioned side having an inturned flap complementing the closure flap and provided with an extension, the side edges of the extension 95 having lips, the lips being bent back and attached to the first mentioned side, the said extension forming an open ended pocket to receive the tongue, and the tongue having 100 catches slidable along the edges of the pocket and adapted to snap over the inner end thereof.

In testimony that I claim the foregoing as my own, I have hereto affixed my signature in the presence of two witnesses.

JOSEPH CALVIN WEBB.
